CLOSURE ALARM

Filed April 27, 1936

UNITED STATES PATENT OFFICE

2,098,635

CLOSURE ALARM

Fred M. Schultz, Detroit, Mich.

Application April 27, 1936, Serial No. 76,616

2 Claims. (Cl. 116—89)

My invention relates to a new and useful improvement in a closure alarm adapted for use on doors, windows and other similar closures so that when the closure is opened an alarm will be sounded.

It is an object of the present invention to provide a device of this class which will be simple in structure, economical of manufacture and highly efficient in use.

10 Another object of the invention is the provision of a closure alarm of this class in which a releasable member will be released upon the opening of the closure and moved to position to explode an explosive cap.

15 Another object of the invention is the provision of a closure alarm of this class so constructed and arranged that the explosive cap will normally be enclosed in a housing and so constructed and arranged that when the housing is moved 20 to position to expose the cap anvil the device will be inoperative to explode the cap.

Another object of the invention is the provision in a device of this class of a novel construction of washer for engaging a spring which serves 25 to actuate the exploding plunger.

Another object of the invention is the provision of a device of this class which will be light, durable and easily and quickly installed in position.

Other objects will appear hereinafter.

30 The invention consists in the combination and arrangement of parts hereinafter described and claimed.

The invention will be best understood by a reference to the accompanying drawing which 35 forms a part of this specification, and in which,

Fig. 1 is a front elevational view of the invention.

Fig. 2 is a top plan view of the invention.

Fig. 3 is a front elevational view of the invention with a part broken away and shown in section.

Fig. 4 is a sectional view taken on line 4—4 of Fig. 3.

Fig. 5 is a sectional view taken on line 5—5 45 of Fig. 4.

Fig. 6 is a side elevational view of the invention showing the housing moved to exposing position.

Fig. 7 is a perspective view of the plunger and 50 washer disassembled.

Fig. 8 is an enlarged fragmentary perspective view showing a locking device in position.

The invention comprises a back plate 12 which may be secured by screws 13 or the like to a suitable supporting body 14. Adjacent the support-

ing body is located the closure 15. Projecting outwardly from the back plate is a boss 16 through which is formed the passage 17. Slidably projected through this passage 17 is the plunger or rod 18 having its upper end angularly turned to provide the abutment arm 19, this arm normally resting above a pair of yoke arms 20 and 21 between which the rod 18 is adapted to slide. The lower end of the rod 18 is tapered as at 22 to provide a head. This head is cut away 10 as at 23 to provide a neck 24 which communicates with a reduced portion 25. An abutment washer 26 having a central opening 27 formed therein is cut away as at 28, this cut away portion 28 being adapted to pass over the reduced 15 portion 25 so that the opening 27 may slide over the neck 24. When the washer is in this position it is locked until it is raised into registration with the reduced portion 25. Embracing the rod 18 and engaging at one end the boss 16 and at 20 the opposite end the washer 26 is a spring 29 so arranged and constructed that when the arm 19 is moved to register with the space between the yoke arms 20 and 21, the spring 29 will force the head or tapered portion 22 downwardly so as 25 to strike the anvil 31 which is carried by the stem 32 pressed into the socket 34 formed on the boss 35 which projects outwardly from the back plate 12. A cup-shaped explosive cap is used which is placed in inverted position over the anvil 31 so 30 that when the device is operated and the plunger or rod 18 is forced downwardly to bring the head or tapered portion 22 into engagement with the cap, the cap will be exploded. When it is desired to lock the device in inoperative position a pin 35 35 may be projected through openings formed in the yoke arms 20 and 21. These yoke arms are beveled as at 37 so that the arm 19 may be thrown to either side from its position of engagement with the pin 36.

40 Formed in opposite sides of the back plate 12, adjacent the rear end thereof, are the grooves 38 and 39 in which engage the inturned flanges 40 and 41 of the U-shaped housing 42. This housing is provided on its upper end with the inturned 45 tongue 43 which will engage the upper face of the boss 16 when moved downwardly to its lowermost position. When moved downwardly to its lowermost position this housing will enclose the anvil and explosive cap so that when the explosion takes place no fire will be permitted to pass from the housing. When it is desired to place a new cap upon the anvil 31, the rod 18 is raised 50 upwardly against the compression of the spring and the arm 19 pressed upwardly, as shown in 55

Fig. 1 or Fig. 8, so as to overlie one of the yoke arms 20 or 21. The tongue 43 will then be in position to prevent a return of the arm 19 into registration with the space between the yoke arm 5 so that when in this position, the housing 42 will serve as a protective guard against undue operation of the device. Should the arm 19 be turned into position for registering between the members 20 and 21 while the housing 42 is raised to its 10 elevated position, the plunger 18 would still not be permitted to slide downwardly with sufficient force to cause an explosion because the housing 42 so snugly engages the plate on which it is slidably mounted as to resist the pressure of the 15 spring 29. It will be noted that the housing projects outwardly beyond the boss 35, thus leaving an opening between these parts. The housing, thus, provides an exploding chamber and the 20 passage or opening referred to provides a sound outlet so that when the explosive cap is exploded, the sound is permitted to escape while the housing forms a shield against flash, flame or particles of the exploded cap.

In use the device is mounted on a suitable support 25 and the arm 19 is swung into position in front of the enclosure, so that when the closure is opened the arm 19 will be swung to register with the space between the yoke arms. As soon as this position is reached, the spring will force 30 the plunger downwardly to explode the cap which is positioned on the anvil 31 and this anvil may be considered an engagement member for engaging the plunger. The plunger may be termed an exploding plunger because it effects an explosion of the cap and when moved to the dotted line position shown in Fig. 4 the plunger may be said to be in operative position, while it may be termed, when moved to the position shown in 35 Fig. 1 or Fig. 3, to be in the cocked position.

While I have illustrated and described the 40 preferred form of construction, I do not wish to limit myself to the precise details of structure

shown, but desire to avail myself of such variations and modifications as may appear within the scope of the appended claims.

Having thus described my invention, what I claim as new and desire to secure by Letters Patent is:

1. A device of the class described, comprising: a supporting member; an engagement member carried by said member adapted for the reception of an exploding cap; an explosive plunger 10 adapted for movement into engagement with said cap for exploding the same; a spring for moving said plunger into exploding position; a laterally turned portion on said plunger; means for engaging said laterally turned portion upon movement of said plunger into cocked position for retaining the same in said position; a housing for enclosing said engagement member, said housing being slidable on said supporting member to position for uncovering said engagement member; and means on said housing upon movement of the same to uncovering position for preventing the disengagement of said laterally turned portion from said means.

2. A device of the class described, comprising: 25 a supporting member; an engagement member carried by said supporting member, adapted for the reception of an explosive cap; an exploding plunger adapted for movement into engagement with said cap, for exploding the same; a spring 30 for moving said plunger into exploding position; means for releasably locking said plunger in cocked position against the compression of said spring; a housing for enclosing said engagement member, said housing being movable on said supporting member to position for uncovering said engagement member; and means on said housing adapted upon movement of said housing to uncovering position for preventing the release of 35 said locking means.

FRED M. SCHULTZ.
